UNITED STATES PATENT OFFICE.

JOHN F. ROBB, OF WASHINGTON, DISTRICT OF COLUMBIA, ASSIGNOR TO KOEHRING MACHINE COMPANY, OF MILWAUKEE, WISCONSIN, A CORPORATION OF WISCONSIN.

CONCRETE-DISTRIBUTING MACHINE.

1,370,497.

Specification of Letters Patent.

Patented Mar. 1, 1921.

Application filed August 11, 1916. Serial No. 114,481.

To all whom it may concern:

Be it known that I, JOHN F. ROBB, a citizen of the United States, residing at Washington, in the District of Columbia, have invented certain new and useful Improvements in Concrete-Distributing Machines, of which the following is a specification.

This invention involves improvements relating to concrete mixing and concrete distributing machines.

In so far as the invention appertains to mixing machines generally, it may be noted that it is becoming well known today that in mixing aggregates such as cement, sand, and gravel, ordinarily called concrete, safe and permanent construction with such aggregates demands that certain precautions be positively insured in the mixing operations. Among these precautions I mention especially those requiring that the aggregates be mixed a predetermined required minimum period, that proper proportions of such aggregates and water be employed, and the prevention of additions to the aggregates previous to their complete admixture and removal from the machine. In my application Serial Number 94754 filed May 1, 1916, I have described certain novel means to avoid possibility of an operator of a mixer interfering, by negligence or for purposes of fraud, with the proper and complete admixture of concrete aggregates placed in the mixer by causing the loading device for the mixer to be actuated to add fresh aggregates to those in the mixer previous to completion of the mixing operation.

One feature of my present invention, therefore, is a continuation of the invention above referred to by so organizing the common mixing, charging, and discharging instrumentalities of such machines that the action of the loading or charging means is controlled directly by the discharging means. The controlling relation mentioned necessitates that the discharge device of my improved machine shall not only be actuated before a new charge of materials can be introduced into the mixer but it must actually wholly discharge the mixer before recharging is possible. I therefore claim as broadly new in this invention provisions for compelling the emptying of mixed materials

from a mixer previous to recharging of the same by whatever suitable charging instrumentality may be employed. In my former invention above mentioned while recharging prior to completion of required time of admixture is provided against, the emptying of the mixer is not compelled though ordinarily it would take place if the operator properly adjusts the discharge means. However, the foregoing suggested improvements, and others now to be briefly set forth, are intended to absolutely insure that a predetermined required treatment of concrete aggregates in process of mixing shall be performed, nothing being left to the imagination, or to chance, as regards what happened in the use of the mixing machine operating on the aggregates, and all this being conducive to that high standard of concrete mixing which skilled engineering makes needful in the interest of safe and sane construction.

Passing to a second phase of the present invention, United States Patent No. 1,141,470 issued June 1st, 1916, to E. H. Lichtenberg exemplifies a type of concrete mixing and distributing machine known as the Koehring paver, used largely in commercial practice today, and to which my improvements are shown applied. In this machine a clutch controls operation of a loading skip which charges the mixer or drum; a lever controls a discharge chute that empties the mixer; manual means control the outhaul movement of the distributing bucket which travels on the boom to the point of deposit of the mixed aggregates, and also the return of the bucket to the mixer, etc. and etc., all of which are separate manually controlled actuating instrumentalities.

A further and important object of my invention has been to devise instrumentalities by which the functioning of the several mechanisms, above mentioned as manually controlled, are coördinated to the extent that with the exception of the skip controlling device they are rendered interdependent and operated automatically in proper order practically under the control of a single means, namely, the actuator that causes loading of the mixer at the outstart. Thus, it is that owing to the coördination of the mechanisms referred to, once the operator

by manual control means raises the loading skip and charges the mixer no other manual means has to be operated by him until the distributing bucket is itself emptied and another batch of aggregates must be introduced into the mixer. That is to say, the operator causes raising of the loading skip and charges the mixer, the skip actuates timing mechanism controlling the discharge which is locked against operation until the time for mixing is completed. The mixing time completed, the discharge is released and operated by automatic means to empty the mixer and during mixing and emptying the skip cannot be raised to recharge. When the contents of the mixer have been emptied therefrom certain clutch mechanisms are set to work and the distributing bucket, which has been filled by said discharge, is thereby caused to move out on its boom until automatically opened and dumped. The bucket after dumping is automatically returned to the mixer and automatically stopped adjacent to the discharge ready to receive another load for distribution. The operation of the discharge to empty the mixer controls the release of certain means that locks the manual device by which the loading skip is raised. Thus a certain required time having elapsed after the discharge is actuated (namely that period necessary for complete emptying of the drum) the manual device is unlocked automatically and the operator is free to actuate it so as to recharge the mixer and by so doing the discharge (chute) is restored to a normal position wherein its discharging action ceases. A new cycle of operation like that just described is now commenced. With my invention the operator of the machine has but one thing to do, namely, to load or charge the mixer, so that the advantages of the invention are quite obvious.

The particular charging, discharging, and mixing devices used for the adaptation of my invention as shown are inconsequential since any suitable construction of such devices having broadly equivalent functions are contemplated to be used. In so far as I am advised, furthermore, it is broadly new to employ combinatively for coördinated automatic action the various mechanisms of a mixing and distributing machine operable substantially in accordance with the cycle of operation above set forth, or even operable according to portions of such cycle.

In the accompanying drawings—

Figure 1 is a side elevation, partly broken away, of a concrete mixing and distributing machine having the improvements of the present invention applied thereto.

Fig. 2 is a vertical sectional view taken through the boom of the machine looking toward the clutch and general control devices adjacent to the inner end of the boom, a por-

tion of the controlling cables being broken away to more fully illustrate adjacent operating parts.

Fig. 3 is an enlarged view in side elevation showing more particularly the controlling instrumentalities at the inner end of the boom and looking at the machine from the side opposite that illustrated in Fig. 1.

Fig. 4 is a horizontal sectional view taken about on the line 4—4 of Fig. 2.

Fig. 5 is a fragmentary sectional view taken about on the line 5—5 of Fig. 6.

Fig. 6 is a view with some parts in elevation and some parts in section, bringing out more fully the operating and release means for the discharge chute and the actuating connections for shifting the clutch mechanism for controlling the operation of the distributing bucket.

Fig. 7 is an enlarged fragmentary and sectional view of the locking and release means for the discharge chute and clutch mechanism.

Fig. 8 is a section taken about on the line 8—8 of Fig. 7.

Fig. 9 is a view of the time controlled governor mechanism, the front plate of the casing inclosing the main parts of said mechanism omitted.

Fig. 10 is an enlarged view partly in section showing certain parts of the clutch shifting mechanism.

Fig. 11 is a view partly in side elevation and partly in section showing more especially the controlling parts intermediate the discharge chute and the clutch operating lever by which the loading skip or charging means is actuated.

Fig. 12 is a view showing more particularly the lock actuating and full stroke compelling means for the skip controlling lever.

Fig. 13 is a sectional view about on the line 13—13 of Fig. 12.

Fig. 14 is a fragmentary view bringing out more clearly the arrangement of the clutch operating abutments mounted on the boom of the machine.

Fig. 15 is a view representative in a somewhat diagrammatic manner of the operating connections intermediate the three armed lever, which is adapted to be tripped by the loading skip, and the timing mechanism as well as the discharge chute actuating shaft.

General construction and arrangement of mechanisms of the machine.

Fig. 1 illustrates a mixing and distributing machine wherein the various operating and controlling instrumentalities used for the purposes of the invention are illustrated without details. The machine shown is of the general type set forth in United States Letters Patent to E. H. Lichtenberg No. 1,141,470 patented June 1, 1915, and No. 1,30

1,185,416 patented May 30, 1916, which machine comprises essentially a mixer in the form of a drum A, loading or charging means for the mixer comprising the skip B, discharging means for the mixer including the discharge chute C operating in a well known manner, preferably of the type shown in Letters Patent No. 899,414 issued Sept. 22, 1908, and distributing means for carrying off and depositing the materials discharged by the chute C including the boom D and the bucket E adapted to traverse said boom.

The various devices A, B and E are intended to be operated by a suitable motor F carried by the truck G which forms the portable base of the machine, operative connections being established between the motor and the skip B by driving connections such as illustrated in United States patent to P. A. Koehring No. 1,107,171 patented August 11, 1914, said driving connections including suitable clutch means for controlling the raising and lowering of the skip B which clutch means in turn is controlled by the lever 1. The bucket E is intended to be moved back and forth on the boom D by cable means connected with trip mechanism on the carriage H which supports said bucket, and which trip mechanism as illustrated is substantially that shown in Patent No. 1,185,416 previously referred to. Said trip mechanism is intended to dump the bucket E by opening its bottom doors as an incident to stopping of the cable 2 during the outward movement of the cable, said doors being restored to closed positions when the bucket E is returned to a point adjacent the mixer A by stopping the cable 2 properly, or by means of the provision of a cam 3 on the boom D, see Fig. 3, which cam is engageable with a restoring arm 4 for normalizing the trip mechanism and thereby closing the doors of the bucket E.

In view of the detail disclosures found in the various patents previously referred to it is deemed unnecessary to recite in detail the action of the general mechanism of the machine except as modified somewhat with a view to adapting the same to the improvements of this invention. It may be noted, however, that the aggregates to be mixed are dumped into the skip or charging device B, are elevated by said device and discharged into the constantly rotating drum or mixer A, are discharged from said mixer A by the chute C into the bucket E, and are conveyed by the bucket E to a suitable point of deposit where they are automatically discharged from the bucket in the well known manner.

With a view to facilitating a comprehension of the improvements of this invention I propose now to describe the various improvements by referring thereto in substan-

tially the order in which said improvements, or the mechanisms in which they are incorporated, are brought into play in what may be considered a complete cycle of operation of the machine from the time of loading the skip B to the time of discharge of the bucket E and the return of said bucket to the mixer ready for another load.

Charging device and mixture time controlling mechanism.

The charging device or skip B is adapted to be raised when loaded by operating the clutch lever 1, as by moving the latter to the right to throw in a clutch which transmits motion to a drum 5, see Fig. 1, which drum is operatively connected by cable means 6 and 7, directly with the skip B. As the skip B reaches the dotted line charging position of Fig. 1, the materials in the skip gravitate into the mixer A and the said action likewise results in a tripping of the three armed lever 8 mounted on the framework of the machine, said lever 8 being connected by a rod 9 with a lever 10. The lever 10 is connected with a rod 11, see Fig. 9, forming a part of the mixture time controlling mechanism, said rod 11 being encircled by a spring 12 disposed in a casing 13 through which the rod operates. On the rod 11 is a projection 14 adapted to be engaged by and to move a lever 15. When the lever 8 is tripped by the engaging action of the skip B the engagement of lever 15 with the projection 14 holds the rod 11 uplifted against the tension of the spring 12 and the movement of the lever 15 exerts a pull on a link 16 connected therewith whereby to shift a bell crank lever 17, the latter being connected with a bar 18 on which is mounted to slide a toothed timing member 19. Normally a spring 20' coacting with the lever 15 and the projection 14 downwardly bearing on the right hand end of the bar 18 holds the member 19 with its teeth disengaged from the worm 20 carried by a shaft 21, which worm is constantly driven through connecting bevel gears 22 and 23, the former on the shaft 21 and the latter on a shaft 24. The shaft 24 has a spur gear 25 meshing with one of the gear rings 26 surrounding the drum or mixer A, the parts 21, 22, 23, 24 and 25 being thus driven from the mixer.

In the casing 13 also is a dog 27 pivoted to a lever 28 which lever is connected by a link 29, the lower end of which, see Figs. 6, 7 and 8 is attached to a pivoted catch 30. The catch 30 engages a stud 31 on a lever 32 carried by the shaft 33 by which the discharge chute C is actuated. Said shaft 33, see Fig. 11, has arms 34 connected by links 35 with arms 36 pivoted at 37 to brackets 38 projecting into the mixer A, the chute C being directly supported by the arms 36

and tilted from the position in which it is shown in Fig. 11 to the discharge position in which it is shown in Fig. 1 by a rocking movement of the shaft 33.

5 The upward movement of the projection 14 with the rod 11 as caused by the actuation of the lever 8 by the skip B results in pushing outward of the dog 27 without affecting the action of the lever 28 and the 10 rod 29, due to the fact that the projection 14 freely slides past the dog, the latter yielding sidewise to permit this action. It being understood that the aggregates have been received by the mixer A and are being 15 mixed, and that the upward movement of the projection 14 has caused the timing member 19 to engage the worm 20, said worm 20 will cause the timing member to move toward the outer end of the bar 18, 20 and the time required for the adjustable tripping arm 39 on the timing member 19 to move against the lower end of the lever 15 represents the required period for effecting a thorough admixture of the materials 25 in the mixer.

The general operation of the timing mechanism is similar to a corresponding mechanism presented in the application for patent of H. A. Trester, Serial Number 89,312, 30 filed April 6, 1916. When the arm 39 contacts with the lower end of the lever 15 the upper end of said lever is withdrawn from engagement with the projection 14 whereupon the latter with the rod 11 is forced 35 downward by the spring 12. As the projection 14 moves downward the heel or outermost portion of the same engages a shoulder on the dog 27 and shifts the latter downward tilting the lever 28 and raising the 40 rod 29. The upward movement of the rod 29 pulls the catch 30 from engagement with the stud 31, see Figs. 6 and 7, whereupon the discharge means or chute C is automatically released and shifted to its discharge 45 position by means of a spring 40 connected with the shaft 33 by which the chute C is actuated. The spring 40 may be of any suitable type and any equivalent device may be used in lieu thereof. The action 50 of the spring, however, is to automatically rock the shaft 33 and force the chute C to its discharge position. This action takes place immediately upon the conclusion 55 of the timing movement of the timing member 19 as caused by the worm 20 seen in Fig. 9.

It may be noted also that the downward restoring movement of the projection 14 on the rod 11 restores the parts 10, 9 and 8 to 60 their normal positions. The projection 14 itself strikes the adjacent end of the bar 18 and lowers the same. The spring 20 forces the lever 15 outward at its upper end, shifts the link 16 and lever 17 and lowers the inner 65 end of the bar 18 whereby the timing mem-

ber 19 is disengaged from the worm 20 and remains so disengaged until the rod 11 is raised again by the actuation of the skip.

The lowering of the member 18 disengaging the parts 19 and 20 permits the spring 70 19^a to pull the timing member 19 back to its normal position in which it is shown at Fig. 9.

Automatic bucket operating mechanism. 75

The cycle of operation of the machine involves movement of the chute C to non-discharging position as the skip B is elevated, a subsequent movement of the chute to discharge position, a complete movement of the 80 bucket E (outward and return), and the return of the skip to lowered position.

Actuating means for certain clutch mechanism is set into operation coincident with the release and movement of the discharge chute C to its discharge position for the purpose of compelling movement of the bucket. 85

Referring particularly to Figs. 4, 6, 7, 8 and 10, it will be observed from Figs. 6 and 90 7 that the lever 32 on the rocking shaft 33 which operates the discharge chute C has a cam 32^a which cam moves in an arc along with the lever 32, when said lever is released from the catch 30. The release of the 95 lever 32 takes place, of course, at the completion of the time of mixing required for the batch of materials in the mixer A and the materials passed through the chute C into the bucket E normally beneath the 100 chute and ready to receive said materials. The clutch mechanism controlling the movement of the bucket E is similar to that shown in Letters Patent to P. A. Koehring, Reissue Number 13,617, reissued September 105 16, 1913, and comprises clutch devices 57 and 58 capable of connecting gears 59 and 60 respectively with a drum shaft 61, the latter supporting a drum 62 about which a cable 63 passes. The gears 59 and 60 are constantly driven in opposite directions by a corresponding bevel gear 64 supported by a shaft 65 seen in Fig. 3, which shaft 65 has a spur gear 66 meshing with one of the gear rings surrounding the mixer drum A. The 110 drum 62 being on the shaft 61 it will be evident that by actuating the clutches 57 and 58 under proper control the drum 62 may be driven in opposite directions and correspondingly drive the cable 63 whereby 115 to move the bucket E outward and inward with its supporting carriage H traversing the boom D.

The movement of the shaft 33 is utilized to throw in the clutch means 58 to operatively connect the gear 60 with the shaft 61 and rotate the drum 62 in such a manner as to carry the bucket E outward on the boom D. The means for doing this includes the cam 32^a on the lever 32 which cam engages 120 125 130

a roller 67 on the lower end of a pull rod 68, see Figs. 6, 7 and 8, as the chute C tilts over to its discharge position. The pull rod 68 in the above action places a spring 69 attached to its upper end under tension, said spring being connected to the rod 70 of the piston 71 in the cylinder 72, said parts constituting an ordinary dash pot. By placing the spring 69 under tension said spring has energy stored up therein exerting a downward pull on the piston 71 and the latter moves downwardly slowly as the air escapes from the lower end of the cylinder 72, the tension of the spring 69 being temporarily maintained owing to the fact that a bolt 73, see Fig. 7, engages a catch 74 on the rod 68 and holds said rod down for the time being after it has been actuated by the cam 32^a. The piston 71 is connected by a rod 75 with a lever 76 which in turn is connected by a bar 77 attached to a lever 78, see Figs. 4 and 6. The lever 78 is adapted to move the pivoted lever 79 connected through a shifting bar 100 with a corresponding lever 80 adapted to shift the clutch device 58 so as to connect the gear 60 with the shaft 61 and thereby effecting the movement of the cable 63 to carry the bucket E toward the outer end of the boom. The dash pot arrangement 71—72 is a delayed movement connection between the shaft 33 and the clutch operating levers 79 and 80 whereby the operation of the clutch 58 does not take place until sufficient time has elapsed for the chute C to discharge the contents of the mixer A into the bucket E. In other words it takes the piston 71 a time equivalent to that required to discharge the mixer, in order to move far enough to throw the clutch device 58 to cause outward travel of the then loaded bucket E, as now to be set forth. When such time has elapsed the lever 78 shifts the clutch device 58 to connect the parts 60 and 61, whereupon the motion of the shaft 61 is communicated to the cable 63 and the bucket E carried outward on the boom D. Later on when the chute C is restored to normal non-discharging position by return movement of the lever 32, the stud 50 of said lever 32 raises the catch 30 slightly and thereby tilts an angle lever 81, an arm of which engages the top of the catch; said angle lever pulling the bolt 73 out of engagement from the catch 74 on the rod 68 and thereby permitting said rod to move upward under the action of a spring 82 connected with the lever 76, which spring is adapted to quickly normalize the parts 68, 69, 70, 71, 75, 76, 77 and 78. The spring 82 will move the piston 71 upward quite quickly once the bolt 73 releases the rod 68 as an air cushion is not formed at the upper side of said piston. A suitable oil contained dash-pot mechanism may be used in lieu of the parts just mentioned if desired.

Automatic dumping of the distributing bucket.

As seen best in Figs. 3, 4, 6 and 14, there is mounted on the boom D a guide bar 83. On said guide bar are freely movable an inner abutment 84 and an outer abutment 85. These abutments 84 and 85 are so located that the supporting frame of the trolley H is adapted to strike the abutments for the purpose of shifting the same relatively to the guide bar 83. A shifting rod 86 is preferably permanently connected with the inner abutment 84 by means of a set screw 84' on the latter and said rod is adjustably connected with the outer abutment 85 by means of a cam locking device 87 whereby said abutment 85 may be connected positively with the rod 86 but the connection established at any desired point in the length of the rod.

At the inner end of the boom D the rod 86 is connected to a shifting slide 88, see Fig. 6, said slide having a curved slot 88' receiving a stud 89 on a yoke 90. The yoke 90 is guided at its lower end by a guide member 91 on a pivoted supporting bracket D' with which the boom D is connected, and at its upper end the yoke is connected by a stem 92 passing through a guide bracket 93 on the framework of the machine, with an arm 94 of frame-like form. The arm 94, see Figs. 6 and 10, is secured at its inner end to a vertical cam and latch bar 95, the latter being guided for vertical movement by members 96 on the bracket 93. Furthermore, a spring 97 normally tends to hold the upper cam head 98 of the bar 95 in engagement with a projection 99 on a shifting bar 100 which is attached at its opposite ends to the lower ends of the clutch operating levers 79 and 80. The shifting bar 100 has a frame-like extension 100^a projecting from its under side and a handle 101 susceptible of manual operation for emergency or other special purposes extends downward from said part 100^a. On the frame-like extension 100^a is a yielding stem 102 having a roller 103 adapted to engage a stud of the bar 95 as well as engage the cam head 98 of said bar.

It being recalled that the last step in the operation of the machine was the effecting of the outward haul of the bucket E along the boom D, it may be noted that as the bucket travels in the direction of the outer end of the boom one of the outermost end portions of the trolley H will ultimately strike the outer abutment 85 and slide said abutment on the member 83, thereby exerting a pull outward on the shifting rod 86 which is connected with the slide 88. Said outward pull on the slide 88 through the provision of the slot 88' and projection 89, seen best in Fig. 5, causes the yoke 90 to be 180

pulled downward and likewise the arm 94 and locking and latch bar 95. It should be understood that when the clutch device 58 was actuated by the lever 79 to connect the gear 60 with the shaft 61 to move the bucket E outward on the boom the bar 95 was held with the clutch device 57 in its operated position owing to the engagement of the bar 95 with the shorter wall of the projection 99 on the bar 100, see Fig. 10. The spring 97 permits of downward yielding of the bar 95 when the lever 78 is actuated to shift the bar 100 to the left as seen in Fig. 10 to obtain the engagement referred to in reference to the parts 98 and 99.

Reverting now to the action of the slide 88 in pulling downward on the parts 90, 92, 94 and 95, it will be apparent that said action by disengagement of the parts 98 and 99 releases the bar 100 and permits equalizing springs 104, seen best in Fig. 4, to carry the bar 100 to a mid position wherein the clutch devices 57 and 58 are inoperative. The action of the springs 104 which are mounted in a bracket 105 on the framework of the machine, is to coöperate directly with an arm 106 projecting between the springs and fixed to the shifting bar 100. The slide 88 not only disengages the cam and latch bar 95 from the projection 99 of the shifting bar 100 whereby to neutralize the clutch mechanism so to speak, but after the bar 95 is disengaged from the projection 99 the cam head 98 moves downward sufficiently to 35 coact with the roller 103 and part 102 to shift the bar 100 in a direction opposite to that in which it was shifted earlier by the lever 78. This opposite shifting of the bar 100 moves the bar a distance sufficient to 40 cause the clutch device 57 to connect the gear 59 with the shaft 61, thereby reversing the rotation of the drum 62 so as to correspondingly reverse the movement of the cable 63 and bucket E. The moment the 45 movement of the cable 63 is stopped and reversed to cause inward haul on the bucket E the trip mechanism 4 carried by the carriage or trolley H and connected with the doors of the bucket in the manner shown in 50 Patent No. 1,185,416, is tripped automatically and the contents of the bucket are dumped. Immediately following the dumping of the bucket E the same is carried inward toward the mixer A in the customary 55 manner.

Stopping of the distributing bucket at the mixer.

The distributing bucket E now traveling inward toward the mixer A again actuates the shifting rod 86 by abutment of an inner end portion of the carriage 8 with the inner abutment 84 on the guide bar 83. The inward shifting of the rod 86 shifts the 65 slide 88 previously shifted outward, in the

opposite or inward direction whereby the stud 89 of the yoke 90 is caused to travel toward the outer upwardly inclined end portion of the slot 88' of the slide 88. This action causes an upward movement of the members 90, 94 and 95 thereby disengaging the roller 103 from the right hand flat side of the cam head 98, as seen in Fig. 10, and restoring the parts 103 and 98 to the relative positions in which they are shown in full lines in Fig. 10. The change thus effected in the relative positions of the parts 98 and 103 permits the neutralizing springs 104 to restore the shifting bar 100 and the clutch actuating levers 79 and 80 to their neutral positions, or in other words to the positions assumed thereby when neither of the clutch devices 57 and 58 is active to connect the shaft 61 and drum 62. Under these conditions obviously the drum is stationary and the cable 63 and bucket likewise stopped, the parts all being ready to be again operated for the outhaul of the bucket on the next actuation of the lever 78.

Locking means for control lever of charging device.

Reverting to the previous suggestion that it is desirable, and in fact necessary, that the charging device B be prevented from being operated so as to add fresh aggregates to those in the mixer, during the mixing operation and before emptying of the mixing drum, it will be observed from Figs. 11 to 13 that the lever 1 controlling the clutch means 41 by which the skip B is adapted to be raised is locked against skip raising actuation by a pivoted locking member 42, see Fig. 13. Furthermore, on the lever 1 is a dog 43 coöoperative with a toothed sector 44 and forming with the sector a full stroke compelling means for the lever 1.

For the most efficient operation of the mixing and distributing apparatus it is desirable that just as soon as the discharge chute C has remained in its discharge position long enough for the discharge of all of the aggregates from the mixer A, the lever 1 be free to be operated to supply a fresh batch of materials to said mixer. With the above in view there is provided on the shaft 33 by which the chute C is actuated a cam 45, see Fig. 11, which cam impinges and actuates a vertically movable bar 46, when the chute C moves to its discharging position. The downward movement of the bar 46 under the action of the cam 45 compresses the normalizing spring 47 surrounding the bar and causes a cam 48 at the lower end of the bar to shift the piston rod 49 connected with the piston 50 forming a part of any suitable delayed movement connection intermediate the discharge chute and the controlling lever 1.

The piston 50 operates in a cylinder 51

and when moved by the cam 48 compresses a spring 52 in said cylinder 51, which spring bears against a second piston 53. Sufficient energy is thus stored up in the spring 52 to force the piston 53 slowly in a rightward direction as seen in Fig. 12, the speed of movement being regulable by a valve 54 controlling an air escape opening provided in a wall of said cylinder 51. The piston 53 has a piston rod 55 an end of which is adapted to engage the locking member 42 and tilt the latter sufficiently to disengage it from the lever 1 whereby to permit of skip raising movement of the lever 1. The movement of the piston 53 is timed so that its piston rod 55 does not impinge and tilt the locking member 42 out of engagement with respect to the lever 41 until the elapse of time sufficient to permit the chute C to entirely empty the mixer A.

As soon as the locking member 42 is disengaged from the lever 1 a spring 42^a engaging said lever 1 forces the latter a slight distance in the direction of its skip raising movement so that the full stroke compelling dog 43 is engaged with the sector 44. Whenever the operator is ready to raise the skip B, therefore, the lever 1 must be forced in a direction to throw in the clutch 41, completing its stroke. When the skip B is properly elevated and the lever 1 partially released for lowering the skip, the full stroke compelling means 43-44 again comes into action and necessitates a full return of the lever 1 to its inactive position in which it becomes locked by the member 42. Thus provision is made against any possibility that the operator of the machine may disturb the action of the timing mechanism by attempting to raise the skip B without fully lowering the same for the reception of a fresh batch of mixed materials. It may require say thirty seconds, more or less, for the mixer A to be emptied of its contents by the chute C, such time varying in accordance with the capacity of the mixer, but once the valve 54 is adjusted properly it will be impracticable for the lever 1 to be manipulated to raise the skip B at any but the proper time, namely after the emptying of the mixer A by the chute C. When the movement of the piston 53 under the action of the spring 50 is completed said piston 53 is restored to normal by a spring 56, the latter being much weaker than the spring 52, and the cylinder 52 having an opening preventing the formation of an air cushion at the left hand end thereof as seen in Fig. 12.

60 Restoring of the discharge chute to normal.

The operations of charging the mixer, discharging the same, actuating the distributing bucket and returning the same, having been completed in regular turn and

the elapsed time for the emptying of the mixer whereby the locking means for the skip raising lever is released having passed, the only thing remaining in the cycle of operation of the whole machine is the restoration to normal of the discharge chute C. This restoration is effected as an incident to the raising of the skip or charging device B for supplying a fresh batch of aggregates to be mixed in the mixer A. The restoring of the chute C takes place at the time the skip B engages and tilts the three armed lever 8, said lever 8 having an additional rod connection 109, see Fig. 1, leading to a bell crank 110 which crank is in turn connected by a rod 111 with a second crank 112. The crank 112 is connected to an arm 113, see Fig. 6, by a rod 114, the arm 113 projecting from the shaft 33 and preferably being an extension of the lever 32 fixed to said shaft. The rocking of the three armed lever 8 when impinged by the skip B effects an upward movement of the rod 114 thereby rocking the shaft 33 in a direction opposite to that in which it is moved by the spring 40, until the stud 31 on the lever 32 is reengaged by the catch 30, whereupon the catch locks the chute which is restored to its non-discharging position in the above action, against being operated to assume a discharge position, until the catch 30 is released in the manner previously described. It is at the time of the reengagement of the stud 31 and the catch 30, just referred to, that the crank 81, see Fig. 7, is tilted and the bolt 73 disengaged from the catch 74 on the rod 68, an action also previously set forth.

Operation of water supply control valve.

In the use of mixing machines of the type to which this invention appertains it is customary for the operator of the machine to open a water supply valve controlling the admission of a proper amount of water to the mixer, at the time when the mixer is charged with the aggregates to be admixed thereby. In carrying out the present invention the above operation, ordinarily manual, is rendered automatic by the provision of an actuating bar 120, see Figs. 1 and 15, which bar is mounted to slide horizontally on the framework of the machine through the provision of any suitable guide means 121. The bar 120 carries an upwardly yieldable gravitational dog 122 adapted to engage a stud 123 upon a valve lever 124 connected with a valve 126 located at a suitable point in the length of a water supply pipe 126. The pipe 126 leads from a water tank 127 mounted on the framework of the machine, preferably above the mixer A, to a point just within the charging end of the mixer, as seen on reference to Fig. 1. One end of the bar 120 is located in a position to be impinged by the lever 8 which, it will be

recalled, is rocked each time the skip B is raised.

Thus it is that when the skip B is hoisted so as to charge the mixer A with a suitable quantity of materials to be mixed the rocking of the lever 8 moves the bar 120 longitudinally and causes the dog 122 on said bar to engage the stud 123 and thus correspondingly rock the valve lever 124 so as 10 to open the valve 125 and permit a predetermined quantity of water to enter the mixer A. At a certain point in the valve actuating movement of the bar 120 the dog 122 passes over or escapes the stud 123 so 15 that the valve lever 124 may be gradually returned to its valve closing position under the action of a spring 128 connected with said lever. The parts 124, 125 and 122 are adapted to be operated so as to close the 20 valve 125 after the necessary quantity of water is admitted to the mixer.

The actuating bar 120 remains in its actuated position so long as the lever 8 remains in its actuated position but will 25 return to its normal position under the action of a spring 120' when the lever 8 is released at the conclusion of the required time for effecting the mixing operation. As the bar 120 returns to its normal position the dog 30 122 yields freely upward and idles over the stud 123 in an obvious manner.

It is to be understood that I do not wish to be confined to the particular automatic means for controlling the opening and closing of the water valve 125 since any suitable means may be employed for the above purpose within the purview of this invention.

Miscellaneous details.

40 The purpose of having an adjustable connection such as 87 intermediate the outer abutment 85 and the shifting rod 86 is to enable the quick and convenient movement of said abutment 85 along the guide bar 45 83 as well as along the rod 86 itself, whereupon the member 85 may be then positively connected with the rod 86. In this way the point where the reversal of the cable and dumping of the bucket E automatically 50 is effected may be varied at will. This is desirable because obviously it is required that the bucket E be dumped at different distances from the machine in accordance with the manner in which the work of laying a pavement or other plastic base progresses.

While I have described above a suitable arrangement for controlling an adjustment of the abutment 85 whereby to effect dumping of the bucket E at different points in the length of the boom D, other constructions may be used for this particular purpose. If desired, indeed, the abutment 85 might be shifted lengthwise of the boom D through 65 the provision of power means, as for in-

stance a screw engaging said abutment and operable either directly or indirectly from the shaft 65 which is constantly driven, any suitable manual device being utilized to control the driving connection whereby the operator may cause shifting of the abutment 85 to the desired point of bucket dumping action.

It is notable that the boom D is intended to swing about a vertical axis designated 107 in Fig. 6, suitable means for moving the boom in a horizontal plane about said axis being provided and substantially the same as described in certain Letters Patent noted herein.

Owing to this peculiar movement of the boom which may approximate an arc of 180 degrees, it is needful that the arm 94 be constructed of frame-like or skeleton formation as seen in Figs. 4 and 6 so that when the boom shifts horizontally the cable 63 will not be interfered with by reason of the provision of the arm 94 disposed transversely to said cable.

Likewise it is contemplated that the boom 90 D be susceptible of vertical movement about a horizontal axis which is designated 108 and seen best in Fig. 5 though illustrated in dotted lines in Fig. 6. On account of this particular movement of the boom the stud 95 89 of the yoke 90 is located concentric or coaxial with the axis 108 so that said stud will always remain in a proper position in the slot 88' of the slide 88 irrespective of the particular angle which said slide 88 may 100 assume as an incident to being raised or lowered with the boom D.

In regard to certain operating connections hereinbefore described, especially those involving the locking and releasing of the operating means for the loading skip and the discharge chute, it may be noted that said connections will preferably be properly housed or inclosed where necessary in order that unauthorized interference with the operation of said connections may be provided against.

Having thus described the invention, what I claim as new is:—

1. In combination, a mixer, means for charging said mixer with materials to be admixed thereby, means for discharging the mixer, and means for compelling emptying of the mixer by said discharging means before the charging means may be operated a second time to introduce a fresh supply of materials to be mixed in the mixer.

2. In combination, a mixer, means for charging said mixer with a batch of materials to be mixed therein, discharging means for the mixer, control means intermediate said discharging means and the charging means whereby to prevent a second operation of the charging means until the said discharging means has been operated.

3. In combination, a mixer, means for charging said mixer with a batch of materials to be mixed therein, discharging means for the mixer, control means intermediate 5 said discharging means and the charging means whereby to prevent a second operation of the charging means until the said discharging means has been operated, and automatic means for operating said dis- 10 charging means at a predetermined time after the materials have been introduced into the mixer by the charging means.

4. In combination, a mixer, means for charging said mixer with a batch of materials to be mixed therein, discharging means 15 for the mixer, control means intermediate said discharging means and the charging means whereby to prevent a second operation of the charging means until the said discharging means has been operated, automatic mechanism for operating said dis- 20 charging means at a predetermined time after the materials have been introduced into the mixer by the charging means, and control means intermediate the charging 25 means and the mechanism above mentioned.

5. In combination, a mixer, a charging device for said mixer, a discharging device 30 for the mixer, means for preventing charging of the mixer by the charging device, and control means intermediate said discharging device and the charging device operable to render said preventing means inac- 35 tive after the discharging device has re- mained in discharging position a sufficient time to discharge the contents of the mixer.

6. In combination, a mixer, a charging device for said mixer, a discharging device 40 for the mixer, means for preventing operation of the charging device, and control means intermediate the discharging device and the charging device for governing the action of said preventing means and com- 45 prising a delayed movement connection operable by movement of the discharge device to discharge position to render the said preventing means inactive only after the discharging device has remained in its dis- 50 charging position a predetermined length of time, so that the charging device may be released for operation on the expiration of such time.

7. In combination, a mixer, a charging 55 device for said mixer, a discharging device for the mixer, means for preventing operation of the charging device, control means intermediate the discharging device and the charging device for governing the action 60 of said preventing means and comprising a delayed movement connection operable by movement of the discharge device to discharge position to render the said preventing means inactive only after the discharg- 65 ing device has remained in its discharging

position a predetermined length of time, so that the charging device may be released for operation on the expiration of such time, and automatic means for operating said discharging device.

8. In combination, a mixer, a charging device for said mixer, a discharging device for the mixer, means for preventing opera- 70 tion of the charging device, control means intermediate the discharging device and the charging device for governing the action of said preventing means and comprising a delayed movement connection operable by movement of the discharge device to dis- 75 charge position to render the said prevent- 80 ing means inactive only after the discharging device has remained in its discharging position a predetermined length of time, so that the charging device may be released for operation on the expiration of such time, 85 automatic means for operating said dis- charging device, and means intermediate the charging device and said automatic means whereby the action of the latter is controlled by the charging device.

9. In combination, a mixer, a charging device for said mixer, a discharging device for the mixer, means for preventing opera- 90 tion of the charging device, control means intermediate the discharging device and the charging device for governing the action of 95 said preventing means and comprising a delayed movement connection operable by movement of the discharge device to dis- charge position to render the said prevent- 100 ing means inactive only after the discharging device has remained in its discharging position a predetermined length of time, so that the charging device may be released for operation on the expiration of such time, 105 automatic means for operating said dis- charging device, and means controlled by the charging device to restore the discharging device to a non-discharging position after said discharging device has been op- 110 erated.

10. In combination, a mixer, a discharg- ing device therefor, automatic means for moving said discharging device from non- discharging to discharging position, a 115 charging device for introducing materials into the mixer, and means intermediate said charging device and the said automatic means whereby one is controlled from the other.

11. In combination, a mixer, a discharg- ing device therefor, automatic means for moving said discharging device from non- discharging to discharging position, a 120 charging device for introducing materials 125 into the mixer, means intermediate said charging device and the said automatic means whereby one is controlled from the other, and means intermediate the discharg- ing device and the charging device whereby 130

the operation of the latter is controlled from the discharging device.

12. In combination, a mixer, a discharging device therefor, automatic means for moving said discharging device from non-discharging to discharging position, a charging device for introducing materials into the mixer, means intermediate said charging device and the said automatic means whereby one is controlled from the other, preventing means coacting with the charging device to prevent its operation until the discharging device has remained in non-discharging position a predetermined time, and means for rendering said preventing means inactive after the discharging device has assumed and remained in discharging position a sufficient period of time to cause emptying of the mixer.
13. In combination, a mixer, a discharging device therefor normally in non-discharging position, a charging device for introducing materials into the mixer to be mixed thereby, means for automatically operating said discharging device, and means intermediate the charging device and said discharging device for restoring the latter to non-discharging position.
14. In combination, a mixer, a discharging device therefor normally disposed in non-discharging position, a charging device for introducing materials into the mixer, automatic means for causing the discharging device to assume discharging position, and mechanism governing the action of said automatic means and controlled by the charging device.
15. In combination, a mixer, a discharging device therefor normally disposed in non-discharging position, a charging device for introducing materials into the mixer, automatic means for causing the discharging device to assume discharging position, mechanism governing the action of said automatic means and controlled by the charging device, and means intermediate the charging device and the discharging device for restoring the latter at a predetermined time after it has assumed discharging position.
16. In combination, a mixer, a discharging device therefor, a controlling mechanism, automatic means for moving the discharge device to discharging position and governed by said time controlled mechanism, a charging device for the mixer, and means intermediate said charging device and the controlling mechanism to govern the action of the latter and intermediate the charging device and the discharging device for restoring the latter to non-discharging position after it has been actuated by said automatic means.
17. In combination, a mixer, a discharging device therefor, a controlling mecha-

nism, automatic means for moving the discharge device to discharging position and governed by said time controlled mechanism, a charging device for the mixer, means intermediate said charging device and the controlling mechanism to govern the action of the latter and intermediate the charging device and the discharging device for restoring the latter to non-discharging position after it has been actuated by said automatic means, lock means for preventing operation of the charging device until the discharging device has remained in discharging position a sufficient time to empty the mixer of its contents, and means controlled by said discharging device for rendering said lock means inactive.

18. In combination, a mixer, a discharge therefor, locking means for said discharge to maintain the same inactive to perform its function, charging means for the mixer, a time controlled mechanism governed by the charging means and coöperating with said locking means to release the discharge therefrom after sufficient time has elapsed for proper admixture of materials introduced into the mixer by the charging device, locking means for preventing operation of the charging device until the said discharge has been rendered active and remained active a sufficient time to empty the materials the admixture of which is completely effected by the mixer.

19. In combination, a mixer, a discharge therefor, locking means for said discharge to maintain the same inactive to perform its function, charging means for the mixer, a time controlled mechanism governed by the charging means and coöperating with said locking means to release the discharge therefrom after sufficient time has elapsed for proper admixture of materials introduced into the mixer by the charging device, locking means for preventing operation of the charging device until the said discharge has been rendered active and remained active a sufficient time to empty the materials the admixture of which is completely effected by the mixer, and operating connections intermediate said charging device and the discharge for causing restoration of the latter to inactive condition.

20. In combination, a mixer, a discharge therefor, locking means for said discharge to maintain the same inactive to perform its function, charging means for the mixer, a time controlled mechanism governed by the charging means and coöperating with said locking means to release the discharge therefrom after sufficient time has elapsed for proper admixture of materials introduced into the mixer by the charging device, locking means for preventing operation of the charging device until the said discharge has been rendered active and remained active a

sufficient time to empty the materials the admixture of which is completely effected by the mixer, operating connections intermediate said charging device and the discharge 5 for causing restoration of the latter to inactive condition, and automatic means for operating the discharge governed by the time controlled mechanism.

21. In combination, a mixer, a discharging device for the mixer, a charging device therefor, a time controlled mechanism, means to control action of the time controlled mechanism from the charging device, automatic means for rendering the discharging device active and comprising a motor, lock means for preventing discharging action of the discharging device adapted to be released by said time controlled mechanism, and operating connections adapted 15 to be shifted in the movement of the charging device for restoring the discharging device to non-discharging position and reestablishing the locking relation of said lock means with respect to said discharging device.

22. In combination, a mixer, a discharging device for the mixer, a charging device therefor, a time controlled mechanism, means to control action of the time controlled mechanism from the charging device, automatic means for rendering the discharging device active and comprising a motor, lock means for preventing discharging action of the discharging device adapted to be released by said time controlled mechanism, operating connections adapted to be shifted in the movement of the charging device for restoring the discharging device to non-discharging position and reestablishing the locking relation of said lock means with respect to said discharging device, a second lock means preventing operation of the charging device while materials introduced into the mixer thereby are being mixed, and a delayed movement connection intermediate the discharging device and the second lock means whereby the latter will be released to permit operation of the charging device when the discharging device has been 25 released and remained in discharging position sufficiently long to cause emptying of the mixed materials from the mixer.

23. In combination, a mixer, a discharge chute therefor, means for locking said discharge chute in an inactive position, automatic means including a motor spring for automatically moving said discharge chute to discharging position, time controlled mechanism for releasing the discharge chute 30 from the locking means aforesaid and permitting it to be operated by the automatic means at a predetermined time after the mixer has been charged, a charging device for the mixer, operating means for said charging device including a main operating

lever, a second lever operable by the charging device connected with the time controlled mechanism to govern the action of the latter, operating connections between said second lever and the discharge chute 70 whereby to restore the latter to inactive or non-discharging position as an incident to operation of the charging device, other locking means coöperating with said main operating lever to prevent operation of the 75 charging device, and a delayed movement operating connection operable from the discharge chute and adapted to release the last mentioned locking means after the discharge chute has remained in its discharging position sufficiently long to cause emptying of the mixer of the materials previously introduced thereinto by the charging device.

24. In combination, distributing means comprising a boom, a bucket adapted to 85 traverse said boom, operating means for said bucket, a discharge by which the bucket is supplied, and means intermediate said discharge and the bucket operating means for controlling the latter from the discharge.

25. In combination, distributing means for distributing materials including a boom, a bucket adapted to travel on said boom back and forth, operating means for said bucket for moving the same away, dumping 95 the bucket and returning the bucket, and discharging means by which the bucket is supplied coöoperative with said operating means for the bucket to cause complete action of said operating means.

26. In combination, distributing means comprising a boom and a bucket adapted to travel back and forth on said boom, operating means for said bucket comprising instrumentalities to move the bucket back and forth and to dump the bucket during its movement and including a cable connected with the bucket, and clutch mechanism governing the operation of said cable, and a discharge chute to supply the bucket coacting with said clutch mechanism for throwing the latter into operation.

27. In combination, a mixer, a discharging device for the mixer, distributing means for materials mixed by the mixer including 115 a support and a bucket adapted to travel on said support toward and from the mixer, operating means for said bucket to cause said movement of the bucket and dumping of the bucket, a charging device for the 120 mixer, mechanism controlled by said charging device for causing automatic operation of said discharging device whereby the latter will discharge the contents of the mixer into the distributing bucket, and means operable by said discharging device for setting in operation the operating means for the distributing bucket.

28. In combination, a mixer, a discharging device for the mixer, distributing means 130

for materials mixed by the mixer including a support and a bucket adapted to travel on said support toward and from the mixer, operating means for said bucket to cause 5 said movement of the bucket and dumping of the bucket, a charging device for the mixer, mechanism controlled by said charging device for causing automatic operation of said discharging device whereby the latter will discharge the contents of the mixer into the distributing bucket, and means operable by said discharging device for setting in operation the operating means for the distributing bucket after said discharging 10 device has remained in discharging position sufficiently long to empty the contents of the mixer into the distributing bucket.

29. In combination, a mixer, a discharging device for the mixer, distributing means 20 for materials mixed by the mixer including a support and a bucket adapted to travel on said support toward and from the mixer, operating means for said bucket to cause said movement of the bucket and dumping of the bucket, a charging device for the mixer, mechanism controlled by said charging device for causing automatic operation of said discharging device whereby the latter will discharge the contents of the mixer into the 25 distributing bucket, means operable by said discharging device for setting in operation the operating means for the distributing bucket after said discharging device has remained in discharging position sufficiently 30 long to empty the contents of the mixer into the distributing bucket, and means operable by the charging device for restoring the discharging device to non-discharging position.

40 30. In combination, a mixer, a discharging device for the mixer, distributing means for materials mixed by the mixer including a support and a bucket adapted to travel on said support toward and from the mixer, operating means for said bucket to cause said movement of the bucket and dumping of the bucket, a charging device for the mixer, mechanism controlled by said charging device for causing automatic operation of said discharging device whereby the latter will discharge the contents of the mixer into the distributing bucket, means operable by said discharging device for setting in operation the operating means for the distributing bucket after said discharging device has remained in discharging position sufficiently 45 long to empty the contents of the mixer into the distributing bucket, means operable by the charging device for restoring the discharging device to non-discharging position as an incident to operation of the charging device for charging the mixer, locking means preventing operation of said charging device, and means controlled from the 50 discharging device for rendering said lock-

ing means last mentioned inactive after the discharging device has remained in discharging position a sufficient time to empty the contents of the mixer therefrom.

31. In combination, a mixer, a discharging device therefor, automatic means for operating the discharging device, distributing means comprising a support associated with the mixer and a bucket adapted to travel along said support to carry mixed materials delivered from the mixer to a suitable point of deposit, operating mechanism for moving said bucket along the support and for causing dumping of the contents of the same, locking mechanism for holding the discharging device in non-discharging position, a time controlled mechanism for releasing the locking mechanism and permitting the discharging device to assume discharge position after sufficient time has elapsed to properly mix materials introduced into the mixer, a charging device for the mixer, means intermediate the charging device and said time controlled mechanism governing the operation of the latter, means intermediate the discharging device and the operating means for said bucket for causing operation of said operating means after the discharging device has reached and remained in discharging position a sufficient time to empty the contents of the mixer into the bucket, preventing means for preventing operation of the charging device while materials introduced into the mixer thereby are being mixed, and instrumentalities intermediate the discharging device and said preventing means to render the latter inactive after sufficient time has elapsed for the discharge of the materials into the bucket by the discharging device.

32. In combination, a mixer, a discharging device therefor, automatic means for operating the discharging device, distributing means comprising a support associated with the mixer and a bucket adapted to travel along said support to carry mixed materials delivered from the mixer to a suitable point of deposit, operating mechanism for moving said bucket along the support and for causing dumping of the contents of the same, locking mechanism for holding the discharging device in non-discharging position, a time controlled mechanism for releasing the locking mechanism and permitting the discharging device to assume discharge position after sufficient time has elapsed to properly mix materials introduced into the mixer, a charging device for the mixer, means intermediate the charging device and said time controlled mechanism governing the operation of the latter, means intermediate the discharging device and the operating means for said bucket for causing operation of said operating means after the discharging device has reached and re-

5 mained in discharging position a sufficient time to empty the contents of the mixer into the bucket, preventing means for preventing operation of the charging device while materials introduced into the mixer thereby are being mixed, instrumentalities intermediate the discharging device and said preventing means to render the latter inactive after sufficient time has elapsed for the discharge 10 of the materials into the bucket by the discharging device, and means operable by the charging device for restoring the discharging device to its non-discharging position.

15 33. In combination, a mixer and operating means therefor, means whereby said mixer may be discharged, means whereby said mixer may be charged and discharged, and means for compelling emptying of the mixer previous to the charging of the same 20 by said charging means.

25 34. A mixing machine of the type comprising charging and discharging instrumentalities combined with means for operating the charging instrumentality, and means whereby a discharging action of the discharging instrumentality is made necessary previous to subsequent charging operation of the charging instrumentality.

30 35. In combination, a mixer, a discharging device therefor, a charging device therefor, and means intermediate said charging device and discharging device whereby to operate the discharging device to cause the latter to effect discharge action of the mixer, 35 and to also operate said discharging device so as to prevent discharging action of the mixer.

40 36. In combination, a mixer, a discharging device therefor, a charging device therefor, means intermediate said charging device and discharging device whereby to operate the discharging device to cause the latter to effect discharge action of the mixer, and to also operate said discharging device 45 so as to prevent discharging action of the mixer.

45 37. A mixing machine of the type comprising a mixer and means whereby said mixer may be charged and discharged, combined with controlling devices necessitating an operation of the mixer discharging means subsequent to each operation of the charging means, and for maintaining said mixer discharging means in effective action long 55 enough to discharge the contents of the mixer.

60 38. A mixing machine of the type comprising a mixer and means whereby said mixer may be charged and discharged, combined with controlling devices necessitating an operation of the mixer discharging means subsequent to each operation of the charging means, and for maintaining said mixer discharging means in effective action long 65 enough to discharge the contents of the

mixer, together with means for rendering the discharging means ineffective from the charging means.

39. A mixing machine of the type comprising a mixer and associated means whereby said mixer may be discharged, combined with a controlling device for causing the discharging means to become ineffective preliminary to charging of said mixer with materials for admixture. 70

40. In combination, a mixer, a discharge therefor, water supply means therefor, distributing mechanism adapted to receive materials from the discharge of the mixer, charging means for the mixer, a main actuator, control means operable by said main actuator for effecting operation of the charging device, and instrumentalities operable successively as an incident to the operation of said charging device by the main 80 actuator for causing water to be supplied to the mixer from the water supply means as an incident to the charging of the mixer by the charging device, to lock the discharge against operation until a predetermined 85 time for completion of the mixing action in the mixer has elapsed and to then operate the discharge to cause the mixed materials to be supplied to the distributing means, and to then cause operation of said distributing means and to finally effect normalization 90 of all the parts.

41. In combination, a mixer, a discharge therefor, water supply means therefor, distributing mechanism adapted to receive materials from the discharge of the mixer, charging means for the mixer, a main actuator, control means operable by said main actuator for effecting operation of the charging device, instrumentalities operable 100 successively as an incident to the operation of said charging device by the main actuator for causing water to be supplied to the mixer from the water supply means as an incident to the charging of the mixer by the charging device, to lock the discharge against operation until a predetermined 105 time for completion of the mixing action in the mixer has elapsed and to then operate the discharge to cause the mixed materials to be supplied to the distributing means, and to then cause operation of said distributing means and to finally effect normalization 110 of all the parts, means for locking said main actuator against operation 115 after charging of the mixer, means to automatically release said locking means after the complete discharge of the contents of the mixer, and full-stroke compelling mechanism co-operative with said main actuator. 120

42. In combination, a mixer, a discharging device therefor, automatic means for moving said discharging device from non-discharging to discharging position, and time controlled mechanism governing the 130

- action of the discharging device to compel the same to remain in non-discharging position a sufficient time for proper admixing of materials in the mixer, and means intermediate the time controlled mechanism and the discharging device to release the latter after its automatic operation when the time for proper admixture of materials by the mixer has elapsed.
43. In combination, a mixer, distributing means therefor comprising a boom, a bucket adapted to traverse said boom, operating means for said bucket, a discharge for the mixer, and means for differentially controlling the bucket operating means in accordance with the position of the discharge.
44. A mixing machine of the type comprising a mixer having associated means for discharging the contents thereof, and for charging the same, combined with control means operable as an incident to the action of the charging means whereby to render the discharging means ineffective for discharging purposes.
45. A mixing machine comprising a mixer, a discharging device therefor and a distributor capable of distributing materials received from the mixer through the medium of said discharging device, combined with controlling appliances whereby the discharging device will discharge materials from the mixer into the distributor and effect operation of the distributor at a predetermined time in the discharging operation.
46. A mixing machine comprising a mixer, a discharging device therefor and a distributor capable of distributing materials received from the mixer through the medium of said discharging device, combined with appliances for causing operation of the discharging device a predetermined time during the admixture of materials in the mixer, and subsequent operation of the distributor at a predetermined time after the discharging device becomes operative for discharging purposes.
47. A mixing machine comprising a
- mixer, a discharging device therefor and a distributor capable of distributing materials received from the mixer through the medium of said discharging device, combined with appliances for causing operation of the discharging device a predetermined time during the admixture of materials in the mixer, and subsequent operation and discontinuance of operation of the distributor at a predetermined time after the discharging device becomes operative for discharging purposes.
48. In combination, a mixer, a discharging device therefor, and automatic means for operating said discharging device at a predetermined time during the mixing operation of the mixer.
49. In combination, a mixer, means whereby to discharge the mixer, means whereby to charge the mixer, and devices operable incident to the action of the charging means to effect discharging and non-discharging operations of said discharging means.
50. In combination, a mixer, automatically operating means for discharging the same, charge introducing means for said mixer, and mechanism operable on operation of said introducing means for controlling the action of said automatic means.
51. In combination, a mixer, means for charging and discharging the mixer, and lock means to prevent operation of the charging means until the discharging device has remained in discharging position a sufficient time to empty the mixer.
52. In combination, a mixer, a discharging device therefor normally in non-discharging position, a charging device for introducing materials into the mixer to be mixed thereby, means for operating said discharging device, and means intermediate the charging device and said discharging device for restoring the latter to non-discharging position.

In testimony whereof I affix my signature.
JOHN F. ROBB.
